CATALYTIC NAPHTHA REFORMING WITH A PLATINUM-ALUMINA CATALYST

John Weikart, Westfield, N. J., assignor to Esso Research and Engineering Company, a corporation of Delaware

Application July 19, 1952, Serial No. 299,826

3 Claims. (Cl. 196—50)

The present invention relates to improvements in the hydroforming of naphthas conducted in the presence of a noble metal such as platinum or palladium. More particularly, the invention relates to a method of regenerating the catalyst with an oxygen-containing gas under conditions more fully set forth hereinafter.

Hydroforming of naphthalene-containing naphthas in the presence of a platinum is a matter of record and commercial practice with respect to fixed bed type of operation. In the prior practice, the hydroforming operation is carried out at very high pressures, namely, of the order of 500 p. s. i. or higher in the so-called non-regenerative type of operation. In this latter type of operation, the hydrogen partial pressure in the reaction zone is maintained at such a high degree that the tendency of carbonaceous deposits to accumulate on the catalyst is repressed, and according to the patents and literature on the subject, the operation may be carried out continuously for an extended period of time without requiring interruption of the process to regenerate the catalyst.

Operating the hydroforming operation in the presence of a noble metal at very high pressures not only is an expensive operation from the standpoint of equipment, such as compressors and reactors which will withstand such pressures at high temperatures, but has the further drawback that the quality of the product is not as high as can be obtained at lower operating pressures.

It has been proposed to operate a hydroforming process using noble metal catalyst under somewhat lower pressures than those indicated above. This operation at lower pressures results in the deposition of carbonaceous material on the catalyst so that it requires periodic regeneration with hydrogen to restore its activity. Hydrogen regeneration of a platinum catalyst has not proven very successful unless the catalyst was regenerated at frequent intervals, or in other words, after it had been in the on-stream operation for a relatively short period of time.

The present invention relates to a process of carrying out the hydroforming of naphthas in the presence of a platinum group metal catalyst while the catalyst is in the form of a dense fluidized bed at relatively low pressures, say, of the order of about 200 p. s. i., whereupon the catalyst acquires carbonaceous deposits. According to the present invention, this catalyst which has been deactivated by accumulation of carbonaceous deposits may be regenerated employing an oxygen-containing gas, under specified conditions more fully set forth hereinafter, to the extent that a small amount of carbonaceous material remains on the catalyst.

Hydroforming may be defined or indicated as an operation in which a virgin naphtha containing a substantial amount of naphthenic hydrocarbons is contacted at elevated temperature and pressure with a suitable catalyst and in the presence of added hydrogen for a sufficient period of time to effect the desired conversion. The main reaction is one in which the naphthenes are dehydrogenated to the corresponding aromatics, but in addition to that, some isomerization of hydrocarbons, and some

2

hydrocracking of paraffins also occurs. The boiling range of the major portion of the feed stock is not substantially altered, although the boiling point of the formed aromatics is substantially higher than the corresponding naphthalene hydrocarbons from which they are formed. The hydrocracking of the paraffins to lower boiling constituents substantially cancels out the effect of the aromatization of the naphthenes to raise the boiling range. Under properly conducted operation, the process results in the formation of a 10 pound Reid vapor pressure gasoline in yields better than 95%. It is a characteristic of this hydroforming operation that there is no net consumption of hydrogen and usually there is a net production of hydrogen.

15 The main object of the present invention is to carry out the hydroforming of virgin naphthas to produce in good yields gasoline constituents of improved octane rating, the operation being carried out in the presence of a noble metal catalyst which is in the form of a dense fluidized bed, and to maintain the catalyst at a high level of activity and selectivity.

Another object of the present invention is to carry out the hydroforming operation using platinum or palladium at pressures substantially lower than those heretofore employed whereby the quality of the product obtained is superior in that the octane value is greater.

Another object of the present invention is to regenerate the platinum catalyst with an oxygen-containing gas.

Other and further objects will appear from the following 30 more detailed description and claims.

In brief compass, the present invention relates to carrying out the hydroforming of naphthas in the presence of a noble metal catalyst of a group consisting of platinum and palladium supported on a suitable base such as active

35 alumina and also containing a minor quantity of hydrogen fluoride, in a two zone system, the first of which is a reaction zone containing a catalyst in the form of a dense fluidized bed, and the second of which is a regeneration zone also containing a catalyst undergoing regeneration 40 while in the form of a dense fluidized bed, further characterized in that the catalyst is not completely regenerated, but rather a relatively small amount of carbonaceous material is permitted to remain on the catalyst as it is returned to the reaction zone. It has been found that by 45 so operating, the activity of the catalyst is maintained at a high value.

In the accompanying drawing there is shown, diagrammatically, the essential elements of an apparatus in which the present invention may be carried into effect.

50 Referring in detail to the drawing, 1 represents a naphtha feed line through which from some source not shown the naphtha to be treated is introduced into the system. From line 1 the oil passes to a heating means such as a fired coil 2 disposed in a furnace setting 3, whereupon it is heated to a temperature of about 900°—925° F.

55 The preheated and vaporized oil is withdrawn from coil 2 and thence pumped by pump 4 through line 5 into reactor 6.

In the interest of heat economy, it is desirable to preheat the cold oil by heat interchange with hot products. This is not shown in the drawing because it is a conventional step in oil refining, generally. A hydrogen-containing gas is also fed to reactor 6. This gas may be withdrawn from an outside source not shown via line 7

60 and charged to a coil 8 disposed in the furnace 9. However, when the process has been onstream for a period of time, sufficient hydrogen-containing gas may be obtained from the product recovery system, and this hydrogen-containing gas is recycled via line 10 to line 7, thus obviating the necessity of using extraneous hydrogen. In coil 8, the hydrogen-containing gas (which is usually of the order of 75—80% purity, the remainder being normally gase-

ous hydrocarbons) is heated to a temperature of about 1000°-1200° F., thence withdrawn through line 3 and charged into the bottom of reactor 6.

It is to be noted that the hot oil and hydrogen gas are not mixed prior to introduction into reactor 6. The purpose of this is to avoid possible thermal cracking of the oil by contact with the hydrogen in the transfer lines.

The hydrogen-containing gas introduced into reactor 6 passes upwardly through a foraminous member G and thence into the bed of catalyst C which, as stated previously, is in the form of a dense fluidized mass, which dense fluidized mass has an upper level L. The velocity of the gaseous material, that is, the oil and the hydrogen-containing gas and other gaseous constituents, is controlled within the limits of from about 1-2 feet per second so as to form the dense fluidized mass referred to. To accommodate this result, of course, the catalyst must have the proper particle size, namely, it should have a particle size of from 0-200 microns, and with over 50% of the catalyst having a particle size of from about 40-80 microns. As to particle size, good results from the standpoint of fluidizable catalyst are obtained when the catalyst has a particle size distribution within the following ranges:

	Weight per cent
0-20 microns	5-10
20-40 microns	20-30
40-80 microns	60-70
80-200 microns	10-15
	100-100

Under the conditions more fully set forth hereinafter, the desired reaction occurs and the raw product is withdrawn from reactor 6 overhead via line 11. The space between L and the top of the reactor is occupied by a dilute suspension of catalyst in gasiform material, the concentration of which decreases upwardly. It is the purpose of this type of operation to effect a separation of the main bulk of the catalyst within the reactor itself, and this is accomplished by providing the disengaging space in the reactor above L. However, to remove entrained catalyst which still is contained in the gasiform material about to emerge in the reactor, the gasiform material is forced through one or more cyclones S wherein these fines are separated and returned to the dense phase via dip pipes d. The raw product in line 11 may still contain entrained catalyst, and if so, may be charged into a scrubber 12 where it is passed countercurrently upward against feed oil, for example, introduced to the top of the scrubber through line 13. This scrubbing oil which is cold causes a partial condensation of the normally liquid constituents, and the feed oil and the condensate serves to remove the last traces of the catalyst in the form of a slurry, which may be withdrawn through line 14 and charged to the bed of catalyst C. The vaporous material is withdrawn from scrubber 12 through line 34 and passed into a separator 15 wherein hydrogen-containing gas is separated and recycled via line 10 to coil 8 for further use in the process. A portion of this gas may be rejected from the system through line 16. The crude product substantially freed from hydrogen is then withdrawn from separator 15 through line 35, thence passed through pressure reducing valve 17, thence passed via line 18 into a second separator 19. From separator 19, normally gaseous constituents, such as methane, ethane and the like, may be withdrawn overhead through line 20 and utilized in any conventional manner for which they are suitable. These gases in line 20 mainly consist of methane and ethane. The desired product is withdrawn from separator 18 through line 21 and passed to a finishing still 22 from which the desired product is recovered overhead through line 23

and collected in a receiving drum 24. Heavy polymer is withdrawn from the bottom of still 22 through line 25, and this material may be either rejected from the system or recycled to line 1 for further treatment. This heavy polymer ordinarily does not amount to more than 2% of the total liquid product.

The catalyst in reactor 6 acquires carbonaceous deposits, particularly, at the low pressures here utilized. Consequently, it will require regeneration. According to the present invention, the regeneration is carried out utilizing air. To this end, the catalyst is withdrawn from reactor 6 via standpipe 26 provided with the usual gas taps t. Through these gas taps a small amount of gas may be injected into the standpipe to prevent bridging, clogging and to otherwise improve the fluidity of the downflowing catalyst. This gas may be some of the recycled gas obtained from line 10. The flow of catalyst in standpipe 26 is controlled by valve 27. The thus withdrawn catalyst is discharged into line 28 containing a stream of air, and the catalyst is picked up by the air and formed into a suspension and carried into the bottom of regenerator 29.

This regenerator is similar in construction to reactor 6 being provided with gas distributing means G₁. Furthermore, the gas velocities in vessel 29 are controlled within about the same limits as those described as prevailing in reactor 6 whereupon a second fluidized bed of catalyst C₁ is formed in the regeneration vessel, which fluidized bed has an upper dense phase level at L₁. The air fed to the bed of catalyst C₁ burns off the carbonaceous deposits and the fumes pass from the regenerator through the disengaging space between L₁ and the top of the regenerator wherein separation of the main bulk of the catalyst from the gasiform material is effected. As in the case of reactor 6 the regenerator is provided with one or more cyclone separators S₁ through which the fumes are forced to separate entrained catalyst, which separated catalyst is returned to the dense phase via dip pipes d₁. The regeneration fumes substantially freed of entrained catalyst pass from the reactor via line 30. As pointed out previously, the catalyst in regenerator 29 is incompletely regenerated so that some carbonaceous material remains on it. The partially regenerated catalyst is then withdrawn from the regenerator 29 via standpipe 31, controlled as usual by valve 32 and charged to the reactor as shown. As usual, the standpipe 31 is provided with gas taps t which provide a fluidizing gas so that the catalyst may flow readily from the regenerator to the reactor.

In the interest of simplicity only the essentials of a suitable apparatus have been described, and those familiar with the art will appreciate that accessory apparatus would be used to improve the efficiency of the process from an engineering standpoint, thus, the skilled engineer will readily appreciate that heat exchanges, flow meters, pressure recorders and temperature recorders etc. would form a part of the apparatus actually used in a commercial installation in the interest of efficiency of operation.

In order to disclose the invention more fully, the following conditions of hydroforming and regeneration giving good results are set forth:

65 Conditions in reactor 6

Catalyst composition	3-1.0% platinum, 0-1.0% HF, 0-5% SiO ₂ , balance active alumina.
Temperature	850-950° F.
Pressure	150-300 p. s. i.
Contact time	1-3 W/H/W ¹ (for 95 octane gasoline).

Cubic feet of hydrogen fed per bbl. of 4,000-8,000 C. F./B. oil (concentration of hydrogen in re-cycle gas).

¹ W/H/W=lbs. of oil per hour per lb. of catalyst in the reactor.

Conditions in regenerator 29

Temperature 900-1000° F.
 Pressure 150-300 p. s. i.
 Pounds of air per 100 pounds of catalyst 0.2-1.0.
 Carbon on catalyst returned to reactor .1-.5, preferably .3-.5.

	Feed	Product
Liquid Product C ₅ +, Yield Vol. Percent on Feed Inspection:	100	86.2
Research Octane No.	51.3	90
Aniline Point	124	39
Gravity	55.2	46
Bromine No.	1.1

C ₃ Wt.	93	1.7
C ₂ Wt.		.5
C ₁ Wt.		.3
H ₂ Wt.		2.4

In order to show the beneficial effect of the partial regeneration of catalyst, the following data are set forth. The regeneration was carried out on a platinum catalyst contaminated during an operation of hydroforming in which the temperature was 900° F., 6,000 cubic feet of hydrogen per barrel was fed with the oil to be hydroformed, the oil feed rate was 1 lb. of oil per hr. per lb. of catalyst in the reactor, and the reaction zone was maintained under a pressure of 200 p. s. i. In the below regenerations which numbered some 14, it will be noted that where the catalyst was partially regenerated the research octane number of the gasoline decreased in value during the onstream period following the first regeneration, but after that there was no further decrease in the octane level of the product during the onstream periods following the next thirteen regeneration phases of the cycle. Where the catalyst was completely regenerated, it will be noted that the research octane number of the product continued to decline after each catalyst regeneration phase until following the 14th regeneration phase or period, it was four points lower than during the corresponding regeneration period in the case where the catalyst was incompletely regenerated.

	Partial Regeneration		Complete Regeneration, Res. Oct. No.
	Percent Carbon on Cat.	Res. Oct. No.	
Fresh Catalyst	0	95.1	97
After 1 Regeneration	.5	89.4	96.5
After 3 Regenerations	.4	91.8	95.5
After 5 Regenerations	.3	90.6	94.5
After 9 Regenerations	.4	91.4	91.0
After 11 Regenerations	.2	91.4	90.0
After 14 Regenerations	.4	91.4	87

To recapitulate briefly, the present invention relates to improvement of fluid catalyst hydroforming of naphthas conducted in the presence of a platinum or palladium catalyst. The process is characterized in that in the interest of improved yield octane relationship, the operation

is carried out at pressures substantially lower than those currently used, for example, in hydroforming naphthas, the conventional fixed bed operation is conducted under pressures of 500 pounds or greater. This type of high pressure operation does not result in the production of a high octane gasoline. The lower pressures employed in the present invention have the advantage that the gasoline produced has an octane number of 95 or higher. Furthermore, excellent yields are secured. Another im-

10 portant aspect of the present invention has to do with maintaining the catalyst at a high activity level by regenerating fouled catalyst with air or other oxygen-containing gas under conditions such that a relatively small amount of carbon remains on the catalyst following the regeneration. Insofar as known, previous attempts to regenerate a platinum type of catalyst have not met with success because after each regeneration the catalyst suffered a severe loss in activity. It has been discovered that by permitting a relatively small amount of material 20 to remain on the catalyst, these severe losses of activity following regeneration with air are avoided.

Numerous modifications of the invention may be made by those skilled in the art without departing from the spirit thereof.

I claim:

1. A continuous method of hydroforming naphthas in a system comprising a hydroforming zone and a catalyst regeneration zone which comprises feeding a naphtha and a hydrogen-containing gas to the hydroforming zone 30 originally containing a fluidized bed of fresh powdered catalyst comprising platinum supported on active alumina, maintaining the hydroforming zone at a temperature of from 850° to 950° F., and a pressure of from 150 to 300 p. s. i. for a sufficient period of time to effect the desired conversion, withdrawing catalyst fouled during the hydroforming reaction, conducting it to a regeneration zone, treating the catalyst with an oxygen-containing gas while in the form of a dense fluidized bed in said regeneration zone until carbonaceous deposits are removed to the extent that the catalyst still contains from .3 to .5 wgt. 40 per cent carbonaceous material, thereafter returning the hot uncooled catalyst to the reaction zone, repeating the above indicated cycle wherein during each regeneration the catalyst is returned to the reaction zone containing the above amount of carbonaceous material following each regeneration and recovering from said reaction zone a product containing gasoline constituents of improved octane rating.

2. The method of claim 1 in which the oxygen-containing gas is air.

3. The method of claim 1 in which the catalyst regeneration is conducted at temperatures above those prevailing in the hydroforming zone.
